SOLDERLESS CONNECTOR

Charles A. Bay, Morristown, N. J., assignor to
Metropolitan Device Corporation, a corporation
of New York

Application November 8, 1938, Serial No. 239,438

1 Claim. (Cl. 24—125)

The invention herein disclosed relates to a connector for connecting electrical conductors and more particularly to a solderless connector in which the two conductors to be electrically connected are mechanically clamped together.

Various attempts have heretofore been made to provide a wire clamp of this type. But such wire clamps as have been suggested are made from forgings, castings or bar stock and commonly employ some form of contact block. Such connectors are accordingly expensive to manufacture and are not as convenient in use as is desired.

An object of this invention is to provide a solderless connector of this type that is constructed from a single strip of metal, that is sturdy and capable of withstanding rough usage, and that is readily and easily applied in connecting two conductors together. This is realized in accordance with this invention by providing a connector that includes a head having a threaded opening therethrough to receive a clamping screw and two substantially parallel arms extending from the head. The arms of the connector are spaced apart and extend from the head substantially parallel to the axis of the opening through the head. The arms have oppositely directed openings to receive the conductors, and the clamping screw clamps the two conductors together.

Such a connector is illustrated in the accompanying drawing in which:

Fig. 1 is a plan view of the connector;

Fig. 2 is a longitudinal section of the same taken on the line 2—2 of Fig. 1;

Fig. 3 is an end elevation of the same taken from the plane indicated by the line 3—3 on Fig. 2; and

Fig. 4 is an end elevation of the same similar to Fig. 3.

In Figs. 1 to 3 of the drawing the connector is shown as it is applied to effect an electrical connection between two stranded conductors 1 and 2. In Fig. 4, the connector is illustrated as it is applied to effect an electrical connection between the stranded conductor 1 and a solid conductor 3.

The connector is constructed from a single heavy strip of metal and consists of a head 4, two substantially parallel arms 5 and 6 and a clamping screw 7. In construction, the strip is first blanked out to obtain the proper configuration. In making the hole 4a through the head 4, the metal of the strip is extruded. In this way a circumferential flange 4b is provided about the openings and provides additional length for

threads 4c that engage the threads of the clamping screw 7.

The arms 5 and 6 are bent to extend from the head in the same direction and parallel to the axis of the hole through the head. These arms 5 extend from diagonally opposite sections of the head so that they are spaced apart in two directions at right angles to each other. The arm 5 has at its extremity an arcuate hook-shaped section 5a and the arm 6 has a similar section 6a. 10 These hook-shaped sections extend in opposite directions. The metal at the hook-shaped sections is extruded and forms surfaces curved transversely and free from sharp edges as clearly illustrated in Fig. 2. The distance between the arms 15 is made equal to the pitch diameter of the screw 7 so that when the head is tapped, threads are also formed in the sides or arms. Additional length of thread contact is thus provided.

In applying the connector, the clamping screw 20 7 is backed off to allow ample room for the hook-shaped sections 5a and 6a of the arms 5 and 6 to pass under the conductors. The connector is positioned with these hook-shaped sections parallel to the axis of the conductor 1 and the connector is then placed over the conductor so that it is embraced by the arms of the connector. Next the connector is turned about the axis of the hole through the head in a direction to cause the oppositely extending hook-shaped sections of the arms 25 5 and 6 to pass under the conductor. The conductor 2 may then be inserted to lie in the hook-shaped sections of the arms and the clamping screw is tightened to clamp the conductors together. With a stranded conductor, such as the 30 conductor 2, the clamping action of the screw 7 causes the strands to spread as shown. In removing the connector, the clamping screw is backed off and the conductor 2 removed. The connector is then turned counter-clockwise as 35 seen in Fig. 1 until the arms 5 and 6 lie, one on each side of the conductor 1 when the connector may be removed.

When the connector is used with a solid conductor such as the conductor 3, the solid conductor is preferably placed directly beneath the clamping screw as shown in Fig. 4. The shape of the head of the connector is such that the conductor is bent on leaving the head in an arc of 40 appropriate radius and there are no sharp edges 45 engaging the conductor.

From the foregoing description of the embodiment of the invention illustrated in the drawing, it will be seen that there is provided by this inven- 50 55

tion a connector that is inexpensive to manufacture and that is reliable in service.

It will be obvious that various changes may be made by those skilled in the art in the details of 5 the embodiment of the invention as illustrated in the drawing and described above within the principle and scope of the invention as expressed in the appended claim.

I claim:

10 A solderless connector of the type described for effecting an electrical connection between two wires which connector consists of a single strip of metal and includes a pair of spaced, parallel, flat arms and a centrally located extruded head integral with the parallel arms and having a threaded

opening therethrough, the axis of which opening is parallel to said parallel arms and midway between the arms and the pitch diameter of which is substantially equal to the distance between the arms, the arms having oppositely directed hook-shaped end sections and the metal thereof extruded outwardly and transversely curved at the hook-shaped sections, and a clamping screw threaded in the hole through the head, whereby two wires within the connector are clamped together between the screw pressing directly on one and the oppositely directed hook-shaped end sections of the arms engaging the other. 5 10
